PLANTER LIGHT OR SIMILAR ARTICLE

Ruth Ann Stevens, Wichita, Kans.

Application May 7, 1949, Serial No. 2,514

Term of patent 7 years

(Cl. D48—20)

To all whom it may concern:

Be it known that I, Ruth Ann Stevens, a citizen of the United States, residing at Wichita, in the county of Sedgwick and State of Kansas, have invented a new, original, and ornamental Design for Planter Light or Similar Article, of which the following is a specification, reference being had to the accompanying drawing forming a part hereof, in which:

Fig. 1 is a front perspective view of a planter light showing my new design;

Fig. 2 is a rear perspective view of the planter light shown in Fig. 1; and

Fig. 3 is a cross-sectional view thereof, taken along the lines 3—3 of Fig. 2.

The dotted lines shown in the drawing are for illustrative purposes only.

I claim:

The ornamental design for a planter light or similar article, substantially as shown, and described.

RUTH ANN STEVENS.
